UNITED STATES PATENT OFFICE.

AXELL A. WEMMERGREN, OF GREAT BEND, KANSAS.

WICK-HOLDING ATTACHMENT FOR LAMP-BURNERS.

No. 825,993.

Specification of Letters Patent.

Patented July 17, 1906.

Application filed March 15, 1906. Serial No. 306,271.

To all whom it may concern:

Be it known that I, AXELL A. WEMMERGREN, a citizen of the United States, residing at Great Bend, in the county of Barton and 5 State of Kansas, have invented certain new and useful Improvements in Wick-Holding Attachments for Lamp-Burners; and I do declare the following to be a full, clear, and exact description of the invention, such as 10 will enable others skilled in the art to which it appertains to make and use the same.

This invention relates to improvements in wick-holding attachments for lamp-burners.

The object of the invention is to provide an 15 attachment by means of which a wick will be firmly held against creeping or moving upwardly or downwardly between the burner.

A further object is to provide means whereby one edge of the wick may be held while 20 the opposite edge is raised or lowered, thus regulating the flame or light and causing the wick to burn evenly.

With the above and other objects in view 25 the invention consists of certain novel features of construction, combination, and arrangement of parts, as will be hereinafter described and claimed.

In the accompanying drawings, Figure 1 is 30 a side elevation of a lamp-burner, showing the application of the invention, parts being broken away. Fig. 2 is a horizontal sectional view through the wick-tube, taken immediately above the wick-adjusting mechanism, showing in full lines the operative position 35 of the attachment and in dotted lines the released or open position of the same. Fig. 3 is a detail sectional view through the wick-tube and the hollow plug of the burner; and Fig. 4 is a sectional view showing a 40 modified form of the attachment.

Referring more particularly to Figs. 1, 2, and 3 of the drawings, 1 denotes the burner, which may be of the usual or any desired construction, provided with a wick-tube 2, said 45 tube being here shown as secured in a hollow plug 3, in which is arranged the wick-adjusting mechanism 4 and by means of which the burner is attached to the lamp-body.

Arranged on the plug 3 is a pivot-plate 5, 50 said plate having formed therein a slot 6, by means of which the same is slipped over the wick-tube, as shown, said plate being held on the plug 3 by a tight frictional engagement with the tube 2. Pivotaly mounted on one 55 end of the plate 5 is a pair of wick-holding le-

vers 7, which are provided near their outer ends with offset outwardly-projecting handles 8, on the outer ends of which are formed downwardly-projecting finger-lugs 9. On the inner edges of the lever 7, near the pivoted end of one and the free end of the other, are formed inwardly-projecting teeth or prongs 10, which are adapted to be projected through alined apertures 11, formed in the wick-tube 2, adjacent to the opposite ends or 60 edges of the same. When the levers 7 are brought to a closed position by the handles 8, formed thereon, the teeth or prongs 10 will be forced through their respective apertures in the wick-tube and through the wick, 65 thereby firmly holding the same against up or down movement. If it should be found that one edge of the wick was burning higher than the opposite edge, one of the levers 7 may be closed and the teeth thereon engaged 70 with one edge of the wick, thereby holding said edge, while the adjusting mechanism 75 may be turned to move the opposite edge of the wick up or down to cause the same to burn evenly, as will be understood.

In Fig. 4 of the drawings the attachment is 80 shown as consisting of but one lever 7^a, said lever being provided with two or more teeth or prongs 10^a, which are adapted to be projected through alined apertures 11^b, formed 85 in the wick-tube, as shown. In the construction shown in Fig. 4 the single lever 7^a is pivoted directly to the top of the plug 3, thus dispensing with the pivot-plate 5, as shown 90 in the first figures of the drawings.

From the foregoing description, taken in connection with the accompanying drawings, the construction and operation of the invention will be readily understood without requiring a more extended explanation. 95

Various changes in the form, proportion, and the minor details of construction may be resorted to without departing from the principle or sacrificing any of the advantages of this invention, as defined by the appended 100 claims.

Having thus described my invention, what I claim as new, and desire to secure by Letters Patent, is—

1. In a lamp-burner, a wick-tube, a lever 105 pivotally mounted upon one end of the wick-tube and extending across the side of said wick-tube, prongs on the side of said lever to engage the wick at opposite sides near the edges and thereby hold the same against 110

moving up or down in the wick-tube, said prongs extending through perforations in said wick-tube, substantially as described.

2. In a lamp-burner, a wick-tube provided with perforations in the sides thereof, levers pivotally mounted at one end of the wick-tube and adapted to be brought into engagement with each side of the wick-tube, and teeth or prongs carried by said levers to project through the perforations in said wick-tube and into the wick at opposite sides thereof and near the outer edges, for the purpose set forth.

3. In a lamp-burner, levers pivotally mounted thereon, offset handles or finger-pieces formed on said levers, laterally-pro-

jecting teeth or prongs arranged on the inner edges of said levers to enter the wick-tube from opposite sides and near the opposite edges of the tube when said levers are brought together, and a pivot-plate adapted to be engaged with said wick-tube to pivotally support said levers in place, substantially as described.

In testimony whereof I have hereunto set 25 my hand in presence of two subscribing witnesses.

AXELL A. WEMMERGREN.
